UNITED STATES PATENT OFFICE.

THEODORE F. VANDEGRIFT, OF SHELBYVILLE, INDIANA, ASSIGNOR TO THE
VANDEGRIFT MANUFACTURING COMPANY, OF SAME PLACE.

NUT-WRENCH.

SPECIFICATION forming part of Letters Patent No. 589,765, dated September 7, 1897.

Application filed November 14, 1895. Renewed August 6, 1897. Serial No. 647,360. (No model.)

To all whom it may concern:

Be it known that I, THEODORE F. VANDEGRIFT, a citizen of the United States of America, residing at Shelbyville, in the county of 5 Shelby and State of Indiana, have invented certain new and useful Improvements in Nut-Wrenches; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to improvements in nut-wrenches of that class which includes a stationary jaw formed integral with the handle and a sliding jaw having members which enter the handle portion, the sliding jaw being adjusted with relation to the stationary jaw by means of a nut which engages the threaded member of the sliding jaw.

In carrying out my invention I make use of a handle portion in which is formed a trans- 25 verse opening for the adjusting-nut and longitudinal openings or recesses which receive the depending members of the sliding jaw, said longitudinal openings or recesses having bearing-surfaces for the members of the sliding jaw to reduce the friction of the moving parts, one of the depending members being threaded for engagement with the adjusting-nut.

The invention also has in view providing 35 the looped or lower end of the handle portion of the wrench of such construction that a filling-block can be applied thereto.

In the accompanying drawings, forming part of this specification, Figure 1 is a side elevation of a wrench constructed in accordance with my invention, the lower part of the handle being of its original configuration before the filling-block is applied. Fig. 2 is a side elevation, partly in section, the filling-block being in position. Fig. 3 is a transverse sectional view on the line 3-3 of Fig. 1, and Figs. 4 and 5 are sectional views on the lines 4-4 and 5-5 of Fig. 2.

A designates the handle portion of the 45 wrench, which is preferably made up of mal-

leable metal forged or cast to provide the looped grasping portion A', rigid jaw A², longitudinal recesses a and a', and transverse opening a². The longitudinal recesses a and a' are located in the upper part of the handle portion A and are provided with reduced annular bearing-surfaces a³ and a⁴, which extend a slight distance into said recesses, the bearing-surfaces a³ being located immediately below the face of the rigid jaw A², while the bearing-surfaces a⁴ are immediately below the transverse opening a².

B designates the sliding jaw, which is provided with depending members b and b', which fit within the longitudinal openings a and a' of the handle portion A, so as to bear against the bearing-surfaces a³ and a⁴ therein. The depending member b of the sliding jaw is screw-threaded for a greater part of its length and engages an adjusting-nut C, which is placed in the transverse opening a² so that the threaded opening therein will be on a line with the longitudinal recess a, which receives said threaded member of the sliding jaw, and when the nut is turned upon the threaded member or shank b the sliding jaw will be drawn toward the rigid jaw, and the member b', which is in the longitudinal recess a' and engages the bearing-surfaces therein, will reinforce the member b against any strain that may come upon the sliding jaw when the wrench is in use.

It will be here noted that as the members b and b' of the sliding jaw contact only with the bearing-surfaces a³ and a⁴ of the handle portion A the friction of the parts is reduced to a considerable extent and permits an easy adjustment of the sliding jaw.

The inner edge of the loop portion A' of the handle is slightly rounded and the upper ends thereof are provided with inwardly-projecting flanges or webs a⁵. Within the looped portion of the handle is placed a block D, the upper end of which is cut away on each side to embrace the flanges or webs a⁵, while the lower and side edges are slightly concave to fit over the rounded edges of said loop. The block is placed in position when the loop is of the configuration shown in Fig. 1, being slid up to engage the flanges or webs a⁵ and

then forced into the loop, after which the side members of the loop are bent inward, as shown in Fig. 2, to firmly hold the block in place.

The lower end of the depending member b' is preferably extended a slight distance below the member b and is cut away on opposite sides, so that the sliding section of the wrench can be removed and used as a screw-driver.

10 I am aware that prior to my invention it has been proposed to provide a nut-wrench consisting of a handle portion having longitudinal recesses and a transverse opening and a sliding jaw having members which slide 15 in the longitudinal recesses, one of the members being screw-threaded to engage a nut let into the transverse opening of the handle portion, and I therefore do not claim such construction broadly; but

20 What I do claim as new, and desire to secure by Letters Patent, is—

25 1. A nut-wrench comprising a handle portion A constructed to present a rigid jaw A^3 , looped grasping portion A' , transverse opening a^2 and longitudinal recesses a and a' having annular bearing-surfaces a^3 and a^4 therein, and a sliding jaw B having members b and b' which slide in the longitudinal recesses a and a' , one of the members being screw-threaded 30 together with a nut C let into the transverse opening a^2 to engage the threaded member of the sliding jaw, substantially as shown and for the purpose set forth.

35 2. In a wrench, the combination, with the sliding jaw having two members one of which is threaded, of a handle portion having a rigid jaw, a looped grasping portion and longitudinal recesses which receive the members of the sliding jaw; a nut let into the handle portion to engage the threaded member of the

40 sliding jaw, webs a^5 extending inwardly from the upper part of the looped grasping portion; and a wooden block D cut away at its upper end to fit into the loop and engage the

webs therein, substantially as shown and for the purpose set forth.

3. The combination in a nut-wrench, of a handle portion A constructed to present a rigid jaw A^3 , looped handle portion A' , transverse opening a^2 to receive the adjusting-nut, and longitudinal recesses a and a' having annular bearing-surfaces a^3 and a^4 ; the looped handle portion being provided with inwardly-projecting webs a^5 ; a sliding jaw B having members b and b' which enter the longitudinal recesses a and a' , one of the members being threaded to engage the adjusting-nut; and a block D having its upper end recessed on each side to engage the webs when placed in the looped handle portion, the side of the looped handle portion being bent in upon the block to retain it in position, substantially as shown and for the purpose set forth.

4. A sliding-jaw nut-wrench, consisting of four parts; to wit, a fixed jaw and integral handle made of a casting or forging to present a jaw A^3 , longitudinal recesses a and a' separated from each other by a central wall and provided with annular bearing-surfaces a^3 and a^4 , the central wall terminating above the lower end of the longitudinal recesses, a transverse nut-receiving opening a^2 , the integral handle having webs a^5 opposite the curved end thereof so as to render the end portions opposite the loop rigid; a sliding jaw having parallel members b and b' , one member being threaded; a nut C; and a filling-block D for the handle, said filling-block being recessed for engagement with the webs a^5 and curved inner edges of the handle; all as shown.

In testimony whereof I affix my signature in presence of two witnesses.

THEODORE F. VANDEGRIFT.
